INTERNAL COMBUSTION ENGINE

Simaan George Warwar, Ramallah, Palestine

Application November 18, 1939, Serial No. 305,149

5 Claims. (Cl. 158—36.4)

This invention relates to internal combustion engines, and more particularly to a means whereby kerosene may be used and burned in an internal combustion engine.

5 At the present time in the operation of certain internal combustion engines kerosene is used as a combustible fuel, but in the use of this fuel it is necessary to provide an auxiliary jet or carburetor whereby gasoline may be initially used 10 so as to heat up the engine to the point where the kerosene will readily vaporize. It is, therefore, an object of this invention to provide a means whereby kerosene may be used during the entire operation of the engine, making it unnecessary to 15 switch from one jet or carburetor to another while the engine is in operation.

Another object of this invention is to provide a structure which may be used with the present parts of a motor vehicle or internal combustion 20 engine, it being only necessary that the carburetor at present in use be adjusted to take care of the heavier fuel or replaced.

A further object of this invention is to provide a structure of this kind wherein the fuel is discharged into a relatively small receptacle in which the fuel is heated to the desired degree and then 25 periodically discharged into an auxiliary tank positioned relatively close to the engine, the fuel flowing by gravity from the auxiliary tank to the 30 carburetor.

A still further object of this invention is to provide a structure of this kind including an auxiliary battery which is used to provide heat for the heating tank, so that the fuel may be 35 heated before the starting of the engine in order that the fuel will be of the proper temperature to vaporize.

With the foregoing and other objects in view, the invention will be more fully described herein- 40 after, and will be more particularly pointed out in the claims appended hereto.

In the drawings, wherein like symbols refer to like or corresponding parts throughout the several views,

45 Figure 1 is a detail side elevation of a motor vehicle chassis having a device constructed according to the embodiment of this invention associated therewith.

Figure 2 is a top plan of the vehicle.

50 Figure 3 is an enlarged fragmentary side elevation of the engine, that portion of the invention adjacent the engine being partly broken away and in section.

Figure 4 is an enlarged vertical section of the 55 fuel heating means.

Referring to the drawings, the numeral 10 designates a motor vehicle frame structure having wheels 11, a radiator 12, hood 13, and a dashboard 14. An engine E is mounted beneath the hood 13 between the radiator 12 and the dashboard 14. The engine E is provided with an intake manifold 15 to which a carburetor 16 is connected. A fuel pump 17 is associated with the carburetor 16, and the pump 17 is connected to the intake manifold 15 by means of a suction 10 pipe 18. While a suction operated pump 17 is here shown, it will be understood that a mechanically operated pump may be used in place of the pump 17.

The hereinbefore described structure is conventional and is here shown as one type of internal combustion engine structure with which the hereinafter described invention may be associated.

A main fuel tank 19 is disposed at the rear of 20 the frame 10 and is provided with the usual filler neck 20. The tank 19 is connected to the suction pump 17 by means of a pipe 21 which has its intake end disposed closely adjacent the bottom of the tank 19, as shown at 22. A fuel heating 25 tank, generally designated as 23, is supported on brackets 24 which are secured to the upper portion of the dashboard 14 by fastening devices 25.

The fuel heating member 23 comprises a cylindrical body 26 having a concave bottom wall 27, 30 and a closure 28 provided with marginal flanges 29 and an air vent 30 engages the upper end of the body 26. A heating element 31 engages about the body 26, and the heating element 31 is constructed in the form of an electrical heating element 35 or coil which contacts with the cylindrical body 26. An outer jacket 32 engages about the heating element 31 and is preferably formed of insulation so as to retain the heat from the element about the body 26. 40

An auxiliary fuel tank 33 is disposed below the heating member 23, being supported on bracket means 34 secured by fastening devices 35 to the dashboard 14. The tank 33 comprises a cylindrical body 36 provided with a concave bottom 45 37 and a closure or top wall 38 having marginal flange 39. The tank 33 is surrounded by a heat insulating jacket so that when the heated fuel is discharged thereinto from the heating member 23 the fuel will not readily dissipate its heat. 50

The tank 33 is connected to the heating member 23 by means of a pipe 41 which at one end is connected to the bottom wall 27 of the heating member 23, and at the other end is connected to the lid or closure 38. The outlet or discharge side of the 55

pump 17 is connected to the heating member 23 by means of a pipe 42. The pipe 42 is connected to a valve housing 43 which is secured to the underside of the closure 28, as shown in Fig. 4, 5 and a valve plug 44 is movable in the housing 43. The housing 43 is provided with an outlet port 45 discharging into the interior of the heating member 23, and an arm 46 is carried by the plug 44.

10 A buoyant member or float 47 is disposed within the heating member 23, being secured to a rock lever or rod 48. The lever 48 is rockably mounted on a shaft 49 which is journaled in a bearing structure 50 fixed to the inside of the body 26 15 adjacent the lower end thereof. An arm 51 is also fixed to the shaft 49 and is provided with an eye 52. The arm 51, as shown in Fig. 4 is disposed on an obtuse angle to the length of the rod or lever 48, and a link 53 connects the eye 52 with the plug arm 46 so that vertical rocking of the 20 lever or rod 48 under the action of the buoyant member or float 47 will move the plug 44 to either a closed or open position.

A cylindrical bushing or boss 54 provided with 25 a bottom flange 55 is secured to the concave bottom 27 within the heating member 23 and in axial alignment with the pipe 41. The flange 55 is provided with a valve seat 56, and the bushing or boss 54 is provided with fluid passages 57 which 30 communicate the heating member 23 with the pipe 41. The bushing or boss 54 is provided with a relatively large bore 58 within which a valve plug or member 59 is adapted to engage. The valve plug or member 59 when in port closing 35 position is adapted to engage on the seat 56 so as to thereby cut off the flow of fuel from the tank or heating member 23 to the auxiliary thermal tank 33.

The upper or inner end of the bushing or boss 54 40 has a cap 60 threaded thereonto, and the cap 60 is provided with a central bore 61 through which a valve stem 62 slidably engages. The valve stem 62 is secured to the valve plug 59 and extends vertically and axially within the body 26. The stem 62 adjacent the upper end thereof 45 is provided with a notch 63, and a second notch 64 is disposed adjacent the lower end of the stem 62, being positioned diametrically opposite from the notch 63. The lever 48 has a valve lifting 50 dog 65 secured thereto by means of a pivotal member 66, and a relatively light spring 67 is carried by the lever 48 and engages the dog 65 so as to constantly urge the dog 65 toward the stem 62.

A valve holding dog 67 is rockably mounted on 55 cars 68 carried by the cap 60, and an arm 69 is formed with the dog 67 and extends laterally of the cap 60. A spring 70 is carried by the cap 60 and engages the arm 69 so as to constantly urge the dog 67 toward the stem 62. The lever 48 is 60 provided with a laterally projecting dog releasing pin 71 which when the float 47 is in the lowermost position is adapted to engage the arm 69 so as to rock the dog 67 to a released position and permit the valve member 59 to drop downwardly 65 to a port closing position. At the time that the float 47 is in its lowermost position, the valve plug 44 is moved to an open position by means of the arm 51, link 53 and arm 46, so that the fuel will be discharged into the heating member 23.

70 The heating member 23 has the element 31 thereof energized by means of a battery 72 which is suitably mounted on the frame 10, and this battery 72 may be in addition to the usual battery 73 which is used in the normal operation of the 75 motor vehicle. The battery 72 is connected to the

heating element 31 by means of a wire 14, and a switch 75 is interposed in the wire 14 so that the heating element 31 may be energized independent of the operation of the motor vehicle. The battery 73 may also be connected to the switch 75 5 by means of a wire 76 so that when desired or necessary the battery 73 may be used to energize the heating element 31.

In the use and operation of the motor vehicle embodying this invention, the switch 75 is initially 10 operated to close the electric circuit to the heating element 31. It will be understood that one side of the heating element 31 is connected to the frame 10, and that one side of the battery is grounded to the frame 10, so that in practice only 15 one wire is necessary to connect the heating element 31 with the battery 72 or the battery 73. The engine E may be initially turned over with the usual starter so as to effect operation of the pump 17 and cause a quantity of fuel to be drawn 20 from the supply tank 19 through the pipe 21 and pipe 42 and discharged into the heating member 23. Assuming that the heating member 23 is initially empty, and that the float 47 is in the position shown in full lines in Fig. 4, the valve 25 plug 44 will be held in an open position permitting the fuel to be freely discharged into the heating member 23. At this time the valve plug 59 will be engaged with the seat 56 so as to cut off flow of the fuel through the pipe 41 to the auxiliary thermal tank 33. The switch 75 may now be closed 30 so as to energize the heating element 31 and thus heat up the fuel in the heating member 23.

The size of the heating member 23 is substantially smaller than the auxiliary thermal tank 35 33 so that only a relatively small amount of fuel will soon fill this member. As the float 47 rises in the heating member 23 the lifting dog 65 will engage in the notch 63 of the stem 62 and thus lift the valve 59 to an open position. When the 40 valve 59 is in an open position the dog 67 will be disposed in a position confronting the notch 64 and will be moved thereinto by means of the spring 70 so that the valve 59 will thus be held in an open position until the float 47 is lowered. 45

When substantially all of the fuel in the heating member 23 has been discharged through the pipe 41 into the auxiliary thermal tank 33 the pin 71 carried by the lever 48 will strike the arm 69 carried by the dog 67 and swing this dog to a released position, permitting the valve 59 to gravitationally drop to a closed position. The fuel in the tank 33 may freely flow to the carburetor 16. If desired the hot exhaust gases from the engine E may be made to circulate about the heating 55 member 23 and/or the auxiliary thermal tank 33, so that after the engine E has been started the heating element 31 may be cut off.

With a structure of this kind the cheaper and heavier fuel, such as kerosene or the like may be 60 used to run the engine, and this fuel may be used during the entire engine operation.

It is, of course, understood that various changes and modifications may be made in the details of construction of this invention, such changes and 65 modifications being dependent only upon the scope of the appended claims.

What is claimed is:

1. An internal combustion engine fuel delivery means, comprising a receptacle, means delivering 70 fuel to said receptacle, an outlet pipe connected to the bottom of said receptacle, a gravity closing valve in said receptacle associated with said connecting means, a second valve in said receptacle associated with said delivering means, a float in 75

5 said receptacle, a rock lever secured at one end to said float, means rockably mounting said lever at the opposite end thereof in said receptacle, a linkage connecting said lever with said second valve, a stem secured to said first valve, said stem having a notch therein adjacent the upper end thereof, and a dog carried by said lever engageable in said notch whereby to lift said first valve to open position upon upward movement of 10 said float.

10 2. Ar. internal combustion engine, fuel delivery means, comprising a receptacle, means delivering fuel to said receptacle, an outlet pipe connecting to the bottom of said receptacle, a gravity closing valve in said receptacle associated with said outlet pipe, a second valve in said receptacle associated with said delivering means, a float in said receptacle, a rock lever secured at one end to said float, means engaging the opposite end of said 15 lever rockably mounting said lever in said receptacle, a linkage connecting said lever with said second valve, a stem secured to said first valve, said stem having an upper and a lower notch therein, a dog carried by said lever engageable with said upper notch whereby to lift said first valve to open position upon upward movement of said lever, a second dog, means rockably mounting said second dog in 20 a position for engagement in said lower notch for holding said first valve in an uppermost open position, an arm carried by said second dog, and a laterally projecting part carried by said lever engageable with said arm upon downward movement of said lever to thereby rock said second dog to released position, said first valve gravitatingly moving downwardly to closed position upon rocking of said second dog to released 25 position.

30 3. A liquid fuel delivery means comprising a receptacle, heating means engaging about the exterior of said receptacle, means delivering fuel to said receptacle, an outlet pipe connected to the bottom of said receptacle, a gravity closing valve in said receptacle associated with said outlet pipe, a second valve in said receptacle associated with said delivering means, a float in said receptacle, a rock lever secured at one end to said float, means engaging the opposite end of said lever rockably mounting said lever in said receptacle, 35 a linkage connecting said lever with said second valve, a stem secured to said first valve, said stem having an upper and a lower notch therein, a dog carried by said lever engageable with one of said notches whereby to lift said first valve to open position, a second dog rockably carried by said receptacle and engageable in the other of said notches when said first valve is in an uppermost position to thereby hold said first valve in open position, and means carried by said lever 40 and said second dog whereby to rock said second

dog to disengaged position relative to said second notch whereby said first valve may gravitatingly move downwardly to closed position.

4. A liquid fuel delivering means, comprising a receptacle, means delivering fuel to said receptacle, an outlet pipe connected to the bottom of said receptacle, a gravity closing valve in said receptacle associated with said outlet pipe, a second valve in said receptacle associated with said delivering means, a float in said receptacle, a rock lever secured at one end to said float, means engaging the opposite end of said lever rockably mounting said lever in said receptacle, a linkage connecting said lever with said second valve, a stem secured to said first valve, said stem having an upper and a lower notch therein, a dog carried by said lever engageable with said upper notch whereby to lift said first valve to open position upon upward movement of said lever, a second dog, means rockably mounting said second dog in 20 a position for engagement in said lower notch for holding said first valve in an uppermost open position, an arm carried by said second dog, and a laterally projecting part carried by said lever engageable with said arm upon downward movement of said lever to thereby rock said second dog to released position, said first valve gravitatingly moving downwardly to closed position upon rocking of said second dog to released position.

30 5. An internal combustion engine fuel delivery means, comprising a liquid heating member, means delivering fuel to said member, a heat insulated receptacle disposed below said member, a pipe connecting said receptacle with said member, a valve in said member connected with said fuel delivery means, a second valve in said member connected with said pipe, a float in said member, a rock lever in said member connected to said float, means carried by said lever engageable with said second valve for moving the latter to an open position upon upward movement of said float, means holding said second valve in open position during the downward movement of said float, means carried by said lever engageable with said holding means for releasing said second valve for gravitating movement to closed position when said float is in a lower position, and a linkage connecting said lever with said first valve for shifting said first valve to an open position when said float is in a lower position and for shifting said first valve to a closed position when said float is in an uppermost position.
